UNITED STATES PATENT OFFICE.

FREDERICK E. KOHLER, OF CANTON, OHIO.

DESIGN FOR A RAKE-HEAD.

SPECIFICATION forming part of Design No. 25,179, dated February 18, 1896.

Application filed January 13, 1896. Serial No. 575,385. Term of patent 7 years.

To all whom it may concern:

Be it known that I, FREDERICK E. KOHLER, a citizen of the United States, and a resident of Canton, county of Stark, State of Ohio, 5 have invented and produced a new and useful Design for a Rake, of which the following is a full, clear, and exact description, reference being had to the accompanying drawings, making part of this specification.

10 My invention relates to a new and useful design for rake-heads; and it consists of a rake-head having the shape and configuration shown in the accompanying drawings, in which—

15 Figure 1 is a front view of the rake-head, and Fig. 2 an end view.

The leading features of my design are the curved or semicircular head or bar 1 and the curved teeth 2, projecting from the lower edge of said bar and formed with the twists 3 at 20 the junction of the teeth with the said bar, thus producing a design that is useful and pleasing to the eye.

What I claim is—

The design for a rake-head as herein shown 25 and described.

In testimony whereof I have hereunto set my hand this 8th day of January, A. D. 1896.

FREDERICK E. KOHLER.
